UNITED STATES PATENT OFFICE.

MARY E. HEINRICH, OF FREEPORT, NEW YORK.

HEADWEAR.

Application filed May 21, 1921. Serial No. 471,393.

To all whom it may concern:

Be it known that I, MARY E. HEINRICH, a citizen of the United States, and resident of Freeport, Long Island, in the county of 5 Nassau and State of New York, have invented certain new and useful Improvements in Headwear, of which the following is a specification.

The invention relates to improvements in 10 head wear and particularly to an article which may be worn as a helmet cap, with strap portions extending downwardly and fastened beneath the chin of the wearer so as to confine the hair; these strap portions 15 also being adapted to be turned up against the sides of the crown portion of the article, the construction being such as to give the appearance of an attractive hat. Such an article will be effective for a variety of uses, 20 such as for automobiling or aviation or other sports, and also for the general purposes to which a hat is to be used.

The objects of my invention are the provision of an attractive, effective and comparatively inexpensive article of the character referred to, and also the provision of improved details of construction and combinations of parts all as will be more fully set forth hereinafter in the following specification, and particularly pointed out in the appended claim. In order that the invention may be more clearly understood, attention is hereby directed to the accompanying drawings forming part of this application 30 and illustrating one embodiment thereof.

In the drawings,

Fig. 1 represents a side elevation of an article of head wear comprising my invention, one of the lower strap portions being 40 shown in its lower position;

Fig. 2 is a similar view, the lower strap portion referred to being shown turned up against the side of the crown portion of the article;

Fig. 3 is a front elevation corresponding to the view shown in Fig. 1;

Figs. 4, 5 and 6, represent the crown member, the strap member and the front flap or brim member, respectively, from 50 which the article is formed, and

Fig. 7 is a view similar to that shown in Fig. 2 with one of the strap portions tucked under the front flap portion.

Referring to the drawings, the cap is 55 formed from a crown member 1, a strap

member 2 and a front flap member 3. These members may all be formed of suitable material, commonly used for making women's hats which may be shaped in the usual way, such, for example, as velvet, straw, silk or 60 the like.

The crown member 1 is so shaped as to fit snugly over the head of the wearer and to provide lower edge portions which are so shaped and positioned as to permit members 65 2 and 3 being secured thereto in their appropriate positions.

The crown member 1, cut out in the form shown in Fig. 4, may be provided with a pair of symmetrically curved upper edges 70 4, 4, which come together at an angle to meet at the point 5 in the vertical center line of the member as shown. The curved edges 4, 4, may be sewed together in any appropriate fashion to form the rounded crown 75 member illustrated in Fig. 1.

Member 1, is provided with lower edge portions 6, 6, which extend inwardly from the two ends of the member at a slight downward inclination for a suitable distance, 80 these edge portions 6, 6, being joined by a central upwardly curved edge portion 7. The front flap portion 3 is provided with an upwardly curved lower edge portion 8 which is adapted to be sewed, or otherwise 85 suitably secured, to member 1 along the edge 7 thereof. When so arranged member 3 will be turned up to stand in front of member 1, over the forehead of the wearer, to present an attractive and jaunty 90 appearance as part of a woman's hat. Member 3 is preferably provided with an upwardly extending peak or point 9 at the center, upwardly extending points 10, 10, also being provided, if desired, at the ends 95 of the member, points 10 and 9 being connected by downwardly curved edges 11. With this construction the point 9 will be positioned at the front of the article, as is shown in the drawings.

Member 2 is provided with an upper edge 12, which is preferably curved slightly with a downwardly concaved curve. The edge 12 of member 2 is adapted to be secured, one-half of the same to one of the edges 6 and 105 the other half to the other edge 6 of member 1. Member 2 is also bounded by a lower upwardly curved edge 13 and inwardly curved side edges 14, 14, whereby downwardly and outwardly extending strap portions 15, 15, 110

are provided, the ends of these strap portions preferably being pointed, as is indicated at 16.

The strap portions 15, thus provided, are provided with coacting fastening means such as a button 17 provided on one of the same and a buttonhole 18 on the other. Strap portions 15 may be extended downwardly and forwardly around the throat of the wearer, and buttoned together in the position shown in Fig. 3, in which position they will, together with the lower side portions of the crown member, enclose the hair of the wearer and prevent the same from being 15 disarranged by the wind.

When it is desired to give the article the appearance of a hat, the strap portions 15 may be turned up about the side edge 12, 6, and extended forwardly against the crown 20 member beneath the pointed ends 10 of flap member 3. Strap portions 15 may, if desired, be secured to the crown member in their turned up positions by providing the crown member and the ends of strap portions 15 with coacting fastening devices, such as coacting fasteners 19, 20, on the crown member and the strap portions 15 respectively. This position of the members is shown in Fig. 2. Or, if desired, the strap 25 ends 15 may simply be tucked under the ends of the flap member 3, and thus held in position, as is shown in Fig. 7. It will be noted that member 2 is so shaped and so connected to the crown member 1 as to permit 30 its adjustment into either of the two positions shown, if desired. This may be accomplished by so shaping members 2 that when they are in the position shown in Fig. 2 the rear edge of each member 2 will extend 35 outwardly, away from the lower rear surface of crown member 1, at an angle, as shown; while when the straps 2 are pulled forward and downward into the position shown in Fig. 7 the rear edge of each strap 40 45 2 will engage against the rear surface of member 1. It is not, however, essential to the invention that both of these forwardly and upwardly extending positions of the

strap portions 15 should be provided for in the same construction.

It will be noted that the end portions 10 of flap or brim member 3 are unsecured to the crown member, although, of course, the central upwardly extending point 9 of the flap member may be secured in position, if 50 desired. Therefore, the flap member will have its end portions spaced away from the crown portion somewhat in the manner of an upturned brim, common in many forms 55 of hat, giving an attractive appearance, and this appearance is not marred when the strap portions 15 are turned up against the crown member, because of the fact that the strap portions extend under the end portions 10 of flap 3. The strap portions 15 are 60 in fact preferably so shaped as to add to the attractiveness of the article when they are turned up and forwardly in the manner described. The flap member 3 may be wired along its edge, and the wire bent in any 65 desired shape.

It will be understood that the invention is not limited to the exact details of construction described, but is as broad as is indicated by the accompanying claim.

What I claim is:

A combined hat or helmet comprising a crown portion adapted to fit the head of the wearer, a front portion adapted to be turned up in front of and spaced from said crown portion, a rear portion curved along its edges to coact with the crown portion and the neck of the wearer, and secured to the lower edge of the crown portion whereby it may be detachably and loosely secured to 80 the forward part of the crown portion with the fullness extending laterally to the sides thereof and behind the turned up front portion when worn as a hat or to be folded downwardly and forwardly and fastened 85 beneath the chin of the wearer when worn as a helmet.

Signed at New York city, in the county of New York and State of New York, this 16th day of May, A. D. 1921.

MARY E. HEINRICH.
